SOUND PICKUP APPARATUS

Barton Kreuzer, Los Angeles, Calif., assignor to
 Radio Corporation of America, a corporation of
 Delaware

Application August 5, 1938, Serial No. 223,237

8 Claims. (Cl. 179—188)

This invention relates to sound-translating devices and particularly to sound wave-to-electrical current translators commonly known as microphones.

The invention is directed to an improvement of the pressure-operated type of microphone, one form of which is disclosed on page 413 of the July, 1936, issue of the Bell System Technical Journal, this type being commonly known as non-directional. In sound motion picture practice a directional type of microphone is generally preferable so as to concentrate on the sounds originating in front of the camera and microphone and to prevent the unwanted and reflected sounds at the rear or sides of the microphone from being recorded.

It has been previously found that the use of a flat baffle or sound wave deflector in connection with a pressure-operated microphone will provide certain directional effects. That is, the sensitivity of the microphone for sounds originating in front thereof is greater than for sounds originating in the rear. The frequency-response characteristics of such a microphone, however, is quite variable with the angle of incidence of the impinging sound waves. This is particularly true at the middle-high frequencies, such as three thousand cycles. In this frequency range, the response is quite high on the standard directional pressure microphone for an angle of zero incidence and falls off quite rapidly at the higher angles of incidence, zero incidence being taken as normal to the diaphragm of the microphone. This condition is particularly undesirable, since it not only provides an unequal frequency response for a particular angle of incidence, but the variation in frequency response between different angles of incidence is not uniform. Thus, if a recording or public address circuit were equalized for a microphone having a particular frequency-response characteristic for zero incidence, the equalization would not be correct for other angles of sound wave impingement.

The present invention, therefore, is directed to an improvement which, although not completely eliminating all inequalities in the frequency response for a definite angle or between different angles of incidence, nevertheless, does flatten these characteristics to produce more uniform response characteristics as well as somewhat reduce the sensitivity at the rear of the microphone. Specifically, the improvement consists of the use of a curved type of baffle instead of the previous flat type, the invention being applicable to any pressure-operated microphone.

both diaphragm and ribbon, although preferable with the diaphragm type.

An object of the invention, therefore, is to make more uniform the frequency-response characteristic of a microphone at a definite angle of incidence.

Another object of the invention is to decrease the variation in the frequency-response characteristics of a certain microphone for different angles of incidence of the sound waves on its diaphragm.

A further object of the invention is to increase the efficacy of a directional type of microphone with respect to sounds emitting between the front and rear thereof.

Although the novel features which are believed to be characteristic of this invention will be pointed out with particularity in the claims appended herewith, the manner of its organization and the mode of its operation will be better understood by referring to the following description read in conjunction with the accompanying drawings forming a part thereof, in which:

Fig. 1 is a partial cross-sectional view of one type of pressure microphone embodying the invention;

Fig. 2 is a plan view of the invention as shown in Fig. 1;

Fig. 3 is another view of the microphone of Figs. 1 and 2 showing the former modification thereof;

Fig. 4 is a graph of the frequency-response characteristics for the microphone of Fig. 3;

Fig. 5 is a graph of the frequency-response characteristics for the microphone of Figs. 1 and 2; and

Fig. 6 is the legend appropriate to Figs. 4 and 5.

Referring now to Figs. 1 and 2, a type of pressure-microphone 4 is shown as having a spherical casing 5 housing the working parts of the microphone, such as a diaphragm 6 with a coil portion 7 positioned between poles of a magnet structure 8. A protective screen 9 is shown bridging the opening in the casing 5. Mounted on three posts 11, 12 and 13, and shown in cross-section, is a spherical baffle 15 attached to the posts by screws 16. There is an opening 18 in the baffle 15 comparable in size with the opening in the casing bridged by the screen 9. Mounted over this opening is a screen 20 held within a ring member 21 fastened to the baffle and microphone by screws 16.

The baffle 15, which was found to provide improved results for a microphone having an outer diameter of approximately 2½ inches, had an

outside diameter of approximately 4 inches, a depth of $\frac{1}{8}$ of an inch, an opening of 1 inch, a wall thickness of $\frac{1}{8}$ of an inch, and a curvature for the outer portion on a radius of $2\frac{1}{2}$ inches. This baffle, applied to the microphone 4, gave more uniform frequency-response characteristics than the flat type of baffle 22, shown in Fig. 3, which had been previously used. This flat baffle had approximately the same diameter as a curved baffle and employed the same screen mounted in the ring 21.

To show the improved results between the two types of baffles, reference is now made to Figs. 4, 5 and 6, Fig. 4 showing measured frequency-response curves for the flat type of baffle for four angles of incidence—namely, 0, 30, 60 and 90 degrees, and Fig. 5 showing the corresponding curves for the baffle of the invention. The abscissas of these curves extend over a frequency range from 70 to 10,000 cycles and have been plotted from data obtained in actual tests run on the two types of microphones. It will be observed, by comparing the curves of Figs. 4 and 5, that in Fig. 4, the curve of zero incidence shows a high response at approximately 3,500 cycles, while the corresponding curve in Fig. 5 is comparatively flat up to 4,000, the peak coming in the neighborhood of 6,000 cycles. This peak is also not of the magnitude of the 3,500 peak in Fig. 4. It will also be noted that the general nature of the characteristics in Fig. 5 are flatter. That is, the variation in response is more uniform for variations in the angles of incidence up to 90°, so that a single equalizing circuit would suffice for all angles. These curves, therefore, actually show the improvement obtained in a sound-to-current translating device by the invention as defined in the appended claims.

Although the particular baffle described above is spherical to improve the spherical type of microphone, it is to be understood that the general shape of the baffle should be such that any definite resonance or reenforcement of response due to the geometry of the baffle with respect to the impinging sound waves be avoided or placed outside the usable portion of the frequency spectrum. Thus, for a certain microphone configuration, the baffle could be made with a wavy contour to further destroy any symmetrical geometry of the baffle with respect to the impinging sound waves.

I claim:

1. In a sound-to-current translating device, the combination of a microphone and a baffle for said microphone, said baffle having an inner flat portion with an opening therein adjacent said microphone and an outer solid surface portion, the outer portion of said baffle being curved to conform to the general external curve of said microphone and having a diameter greater than the diameter of said microphone.

2. In a sound-to-current translating device, the combination of a pressure type microphone having a casing and a diaphragm for the impingement of sound waves thereon, an opening

in said casing for the entrance of sound waves to said diaphragm, and a sound wave deflector adjacent said opening having an inner portion with a screened opening therein and an outer solid surface portion forming a continuation of said inner portion and having a diameter one-half greater than the diameter of said microphone.

3. In a sound-to-current translating device, a spherical pressure type microphone having an opening in one side thereof for the entrance of sound waves, and a spherical baffle having a flat portion with an opening therein immediately adjacent said microphone opening, the outer surface of said baffle and said microphone having substantially the same curvature, the diameter of said baffle being approximately one-half greater than the diameter of said microphone.

4. A sound wave deflector for sound waves being received comprising a circular flat portion having an opening therein, said opening having a diameter of substantially one half that of said flat portion, and being centrally disposed within said flat portion, and a solid surface spherical portion surrounding said flat portion.

5. A sound wave deflector for sound waves being received comprising a substantially flat portion having a plurality of openings therein, said openings extending over an area having a diameter of substantially one half that of said flat portion and being centrally disposed within said flat portion, and a solid surface second portion forming a continuation of said flat portion and of substantially uniform curvature.

6. A sound wave deflector for sound waves being received comprising a substantially flat portion having an opening therein and a second portion forming a continuation of said flat portion and of substantially uniform curvature, said flat portion being approximately two inches in diameter with a screen covering said opening, said opening being approximately one inch in diameter, the diameter of said curved portion being approximately four inches.

7. In a sound-to-current translating device, a microphone approximately three inches in diameter and a baffle for said microphone, said baffle having an inner portion of approximately two inches in diameter with an opening therein of approximately one inch in diameter and an outer curved portion of approximately four inches in diameter, the outer portion of said baffle having a curvature on a radius of approximately two and one-half inches.

8. In a sound-to-current translating device, a microphone approximately three inches in diameter and a baffle for said microphone, said baffle having an inner flat portion of approximately two inches in diameter with a flat screened opening therein of approximately one inch in diameter, and an outer curved portion of approximately four inches in diameter, the outer portion of said baffle having a curvature on a radius of approximately two and one-half inches.

BARTON KREUZER.
